UNITED STATES PATENT OFFICE.

WILLIAM F. ULLRICH, OF WARREN, PENNSYLVANIA.

PROPELLENG MECHANISM FOR BOATS.

1,320,511.

Specification of Letters Patent.

Patented Nov. 4, 1919.

Application filed August 27, 1917, Serial No. 188,460. Renewed March 17, 1919. Serial No. 283,283.

To all whom it may concern:

Be it known that I, WILLIAM F. ULLRICH, citizen of the United States, residing at Warren, in the county of Warren and State 5 of Pennsylvania, have invented certain new and useful Improvements in Propelling Mechanism for Boats; and I do declare the following to be a full, clear, and exact description of the invention, such as will enable others skilled in the art to which it 10 pertains to make and use the same.

My invention relates to improvements in propelling mechanism for vessels and the like.

15 The principal objects of my invention are to provide a novel and improved propeller, an improved mounting therefor, and an improved driving means therefor.

An additional object of the invention is to 20 provide a novel construction of propeller mechanism of the character described, in which the parts of the driving gearing are fully protected from weeds and the like and in which most efficient power and utility is 25 secured.

With these and other different objects in view which will appear from the description, the invention resides in the novel construction, combination and arrangement of 30 parts, to be more fully hereinafter described and claimed and taken in connection with the accompanying drawings which form a part of this specification and in which:—

Figure 1 is a side elevation of the preferred form of my invention.

Fig. 2 is a central, vertical, longitudinal section thereof, on an enlarged scale.

Fig. 3 is a transverse vertical section on the line 3—3 of Fig. 2.

40 Fig. 4 is a side elevation of the modified form of my invention.

Fig. 5 is a central vertical, longitudinal section thereof, on an enlarged scale.

Fig. 6 is a transverse vertical section on a 45 line 6—6 of Fig. 5.

Briefly described, my invention comprises a tubular casing to be attached at one end, to a vessel. Rotatably mounted rings having propeller blades secured thereon, are 50 positioned on the exterior of the casing and the drive shaft of the engine of the vessel is extended into the casing and is connected by

means of suitable gearing with the rotatable rings, in such a manner as to oppositely rotate the rings.

55 In the accompanying drawings I have illustrated in detail certain approved forms of my invention, but it is to be understood that various changes and modifications may be made in the structure to be described herein as may fall within the scope of the invention as claimed. Therefore, I do not intend to limit myself to the specific construction and details employed and described.

No. 1 in the accompanying drawings designates a vessel at the stern of which is mounted a rearwardly extending tubular casing 2. The casing 2 is suitably secured to the vessel in any approved manner as desired, and is reduced throughout a portion 70 of its length to its outer end to provide the shoulder 3 at its inner end. In this approved form of my invention the casing 2 is engaged over or mounted on a projecting portion 4 of the vessel and is suitably secured thereto. The outer end of the casing is closed by a removable plug 5, so that access may be readily obtained to the interior of the casing to reach the mechanism located 75 therein as hereinafter described.

80 The engine driving shaft 6 is extended rearwardly projecting into the casing and is supported therein in a bearing 7 mounted on a bracket 8 extending transversely of the casing and secured at its ends to the walls 85 thereof. A stuffing box 9 is provided at the rear of vessel for the shaft 6 where it enters the interior of the casing 2.

The upper portion of the casing 2 is provided with a transversely extending slot 10 90 and disposed in this slot, and extending slightly thereabove is a pinion 11 keyed on to the driving shaft 6. On the reduced portion of the casing adjacent the shoulder 3 at the inner end thereof is a rotatably 95 mounted ring 12 retained thereon by means of an annular retaining ring 13 threaded on the casing intermediate the ends thereof. The outer face of the ring 12 is disposed flush with the outer face of shoulder 3, and body of ring 12 is supported between the shoulder and retaining ring 13 in spaced relation from the outer surface of the casing 2, as clearly illustrated in Fig. 2.

The opposed faces of the ring 12, shoulder 3 and retaining ring 13 are suitably recessed to receive annular series of ball bearings 14 for antifrictional mounting of the rings. 5 Suitably secured to the outer face of ring 12 are propeller blades 15.

A second ring 16 is mounted on the reduced portion of the casing at the opposite side of the retaining ring 13 and supported 10 between the retaining ring 13, and a retaining nut 17 disposed over the outer end of the casing. Ball bearings are provided as in the mounting of ring 12 and the propeller blades are secured to the outer faces of the 15 rings as in the manner of construction of ring 12. The rings are designed to rotate in opposite directions and the propeller blades thereon are angled as illustrated in Fig. 1, so that the rearward thrust of the water 20 from the face of the forward propeller will assist in the operation of the rearward propeller. The opposite faces of the propeller rings 12 and 16 are provided with bevel gears. At spaced intervals, disposed in mesh 25 with these gears are pinions 18 loosely secured in the ring 13 by means of suitable spindles 19. The inner faces of the propeller rings are concaved longitudinally to provide bearing portions at the ends thereof 30 and to also provide a construction whereby friction between the propeller rings and casing will be reduced in proportion.

The propeller ring 12 adjacent the vessel is provided with an annular series of internally disposed cogs 20 in alignment with 35 the slot 10 and disposed in mesh with the pinion 11 for driving connection with the propeller rings. It will be seen that when the shaft is rotated, movement will be imparted through pinion 11 and annular gearing 20, to the ring 12, which will in turn impart reverse movement to ring 16 by means 40 of pinion 18 as described. Owing to the construction of the inner faces of propeller bearing rings, and mounting of said rings 45 between the retaining members and the shoulder of the casing, friction will be reduced; and, as the driving connection and gearing is disposed in the interior of the 50 casing, the only parts of the mechanism exposed will be the propeller blades. Whenever it is desired to gain access to the interior of the casing to adjust or clean gearing or other parts, the plug 5 may be readily 55 removed when desired. In Figs. 4, 5 and 6 I have illustrated a modified form of my invention, in which the general arrangement of parts is identical with the construction and location of the parts so illustrated in 60 Figs. 1, 2 and 3, but in the modified form the driving shaft 6' is made hollow, and disposed concentrically therein is a second driving shaft 21 projecting rearwardly into the casing and has a pinion 22 mounted on its

outer end. A transversely extending slot 23 65 is provided in the casing in alignment with an internal gear 24 formed on the rearward propeller ring. The pinion 22 is meshed with the internal gear 24, and the end of shaft 21 is supported in a bearing formed 70 on a transversely extending brace bar or support 25.

Opposite rotation of the rings is accomplished by the opposite actuation of shafts 6' and 21 which are suitably arranged for 75 driving connection with the engine of the vessel, the arrangement and details thereof not being shown.

While in the foregoing description, I have specifically described the construction and 80 operation of my propeller, I desire it to be understood, that minor changes may be made within the scope of the invention as claimed.

I claim:

1. A propeller comprising a casing having an opening therethrough, propeller blades, a plurality of rotary elements extending around said casing and carrying said propeller blades, means within said casing and 90 extending through said opening and operable to rotate one of said rotary elements in one direction around said casing, and transmission gearing whereby the other of said rotary elements is rotated in the opposite 95 direction.

2. A propeller comprising a tubular casing, rings disposed around said casing, propeller blades carried by said rings, an annular retaining and bearing member around 100 and secured to said casing between the blade-carrying rings, bearing elements co-operative with said bearing and retaining member for rotatably supporting said blade-carrying rings, and means extending outward from the interior of the casing and being operable to effect rotation of the blade-carrying rings.

3. A propeller comprising a tubular casing, rings disposed around said casing, propeller blades carried by said rings, an annular retaining and bearing member around 110 and secured to said casing between the blade-carrying rings, bearing elements co-operative with said bearing and retaining member for 115 rotatably supporting said blade-carrying rings, and means disposed exteriorly of the casing and operatively connected with said rotary elements, whereby one of the rotary elements effects rotation of the other rotary 120 element.

4. The combination with a vessel of a tubular casing attached thereto at one end and projecting therefrom and having openings therethrough, rings rotatably 125 mounted on said casing, propeller blades on said rings, annular retaining members threaded on said casing to space said rings

and provide supports therefor, ball bearing connections between said rings and members, and means in said casing and extending through said openings and operable to oppositely rotate said rings.

5 In testimony whereof I have hereunto set

my hand in the presence of two subscribing witnesses.

WILLIAM F. ULLRICH.
